PULL TAB FOR A TEAR STRIP OPENER

Warren J. Hayford, Greenwich, Conn., assignor to Continental Can Company, Inc., New York, N.Y., a corporation of New York

Filed Oct. 15, 1965, Ser. No. 87,518

Term of patent 14 years

(Cl. D58—26)

FIG.1

I claim:

The ornamental design for a pull tab for a tear strip opener, as shown.
